COMBINED SHOCK ABSORBER AND SPRING LUBRICATOR

Filed July 28, 1927

UNITED STATES PATENT OFFICE.

WALKER H. SPAYD, OF VAN WERT, OHIO.

COMBINED SHOCK ABSORBER AND SPRING LUBRICATOR.

Application filed July 28, 1927. Serial No. 209,019.

The invention relates to a new and improved device for effectively lubricating the leaves of a vehicle spring and at the same time holding a number of said leaves together with sufficient friction to effectively absorb shocks which would otherwise take place.

One object of the invention is to provide a device of the class set forth provided with novel means for securing it in place upon a spring.

Another aim is to make unique provision to compensate for the extra space which exists in the device when it is applied to only three spring leaves instead of four, or to some other relatively small number of leaves instead of a larger number.

A still further object is to provide a novel arrangement of capillary pads or wicks for feeding oil to the spring leaves from an oil receptacle which also acts as retaining means for a spring which frictionally holds the spring leaves in contact with each other.

A still further object is to make novel provision for packing the oil receptacle against entrance of dust and other foreign matter.

Yet another aim is to provide a device which will be rather simple and inexpensive, may be easily applied and will be very efficient and durable.

With the foregoing in view, the invention resides in the novel subject matter herein-after described and claimed, the description being supplemented by the accompanying drawings.

Fig. 1 is a side elevation showing the application of the device.

Fig. 2 is a side elevation partly broken away and in section.

Fig. 3 is a sectional view through the vehicle spring and side elevation of the shock absorber and lubricator, as indicated by line 3-3 of Fig. 1.

Fig. 4 is a vertical sectional view on line 4-4 of Fig. 3.

Fig. 5 is an additional vertical section on line 5-5 of Fig. 4.

Figs. 6 and 7 are horizontal sectional

views on the correspondingly numbered lines of Fig. 4.

Fig. 8 is a perspective view of one of the T-shaped capillary wicks or pads.

The drawing above briefly described illustrates a construction which has in actual service, proven to be desirable from all standpoints and exceptionally efficient. Hence, this construction may be considered as representing the preferred form of the invention, with the understanding however that within the scope of such invention as claimed, variations may be made.

The device embodies an oil receptacle 10 which is preferably of cylindrical form and open at its upper end. This upper end is provided with a continuous laterally projecting flange 11 which is preferably of substantially square outline, as seen in Fig. 7. Integral with and rising from opposite side portions of the flange 11, are two parallel vertical flanges 12 to straddle a number of the leaves of a vehicle spring 13. Between the upper portions of these flanges 12, a block 14 is provided to overlie the spring 13, opposite edges of said block being formed with ribs 15 receivable in grooves 16 in the inner sides of the flanges 12, when the block is horizontally slid into position between said flanges. These co-acting ribs and grooves hold the flanges 12 and block 14 against relative vertical movement, and relative horizontal movement of these parts is prevented by a bolt 17. This bolt is receivable in a transverse groove 18 formed in the lower side of the block 14 and its ends pass through openings 19 in the flanges 12, the bolt being preferably threaded into one of these openings as shown in Fig. 5. The lowermost portion of the bolt 17 is either flush with or somewhat above the lower side of the block 14 so that when four leaves of the spring 13 are received between the receptacle 10 and the block, the latter may rest directly upon the uppermost leaf. However, when the device is applied to only three leaves of a spring as herein disclosed, a filler plate 20 is positioned under the block 14 to occupy the space which would otherwise exist. The upper side of this plate 100

is formed with a rib 21 whose upper portion is grooved as at 22 to engage the bolt 17, in which connection, it will be observed that this bolt is spaced from the opposite side walls of the groove 18. To decrease weight and economize in material, the plate 20 may well be provided with a central opening 23.

A heavy, coiled, compression spring 24 is vertically positioned in the oil receptacle 10 to force upwardly upon the spring 13 and downwardly upon said receptacle, thus tightly holding the leaves of said spring in contact with each other. The lower end of this spring rests upon a plate 25 preferably having an upstanding, spring-received stud 26 at its upper side and a shallow socket 27 in its lower side. An adjusting screw 28 is threaded through the lower end of the oil receptacle 10 and engages the socket 27, permitting the strength of the spring 24 to be varied as occasion may demand.

The inner opposed sides of the flanges 12 are formed with shallow recesses 29 and the inner side of the oil receptacle 10 is formed with vertical grooves 30 leading downwardly from said recesses. T-shaped capillary pads or wicks such as that shown in Fig. 8, have their head portions 31 received in the recesses 29 and their shank portions 32 received in the grooves 30, fluid-proof glue or cement being employed in most instances to hold said heads and shanks in place. Thus, the wicks or pads 31-32 served by capillarity, to feed oil from the receptacle 10 to the edges of the spring leaves so that it may permeate between them to produce effective lubrication, thus insuring easy action of the spring, even though its leaves are bound frictionally together by means of the device.

To exclude dirt, mud and the like from the oil receptacle 10, I provide packings 33 extending between the vertical edges of the flanges 12 for contact with the lower side of the spring 13, these packings being held in grooves 34 in the portions of the flange 11 which extend between said flanges 12.

To apply the device, the bolt 17 is removed, permitting horizontal sliding of the block 14 from the space between the flanges 12. Then, the entire device may be upwardly forced so that the flanges 12 straddle the spring 13, the screw 28 being then loosened to permit the necessary upward movement of the device for the purpose of allowing reinsertion of the block 14 with ease, and positioning also of the plate 20 if the latter is to be used. The bolt is now re-positioned and when this is done, the screw 28 is tightened, thereby placing the spring 24 under compression. This screw may be so adjusted as to obtain the desired amount of friction between the spring leaves, thus insuring excellent riding qualities of the machine as

well as effective lubrication of the spring. As the vehicle spring 13 flexes, the upper leaf which engages the plate 20 or the block 14 as the case may be, and the lower leaf which engages the spring 24, necessarily have some relative longitudinal movement. During this movement, the spring 24 has a rocking motion which is permitted by the engagement of the plate 25 with the rounded upper end of the set screw 28. By allowing the spring to rock in this manner, its upper end does not have to slide upon the lower leaf of the vehicle spring, and consequently said spring will remain in proper relation with the other parts of the device.

As above stated, the construction herein specifically described, is preferable. However, attention is again invited to the fact that within the scope of the invention as claimed, variations may be made.

Attention is invited to the fact that the receptacle 10 and its side flanges 12, together with the spring 24 and its connection with said receptacle, constitute a yoke structure co-operating with the fastener 17 and the grooved plate 20 in yieldably holding the leaves of the vehicle spring in contact with each other, hence acting as a shock absorber, even though the lubricating feature of the invention be eliminated.

I claim:

1. A combined shock absorber and spring lubricator comprising an oil receptacle provided at its upper end with upstanding flanges to straddle a spring, a block horizontally insertable between said flanges to overlie the spring, said flanges and block having inter-engaged ribs and grooves to hold them against relative vertical movement, means for holding said flanges and block against relative horizontal movement, spring means in said receptacle for forcing upwardly on the spring and downwardly on the receptacle, and capillary means for feeding oil from the receptacle to the spring.

2. A combined shock absorber and spring lubricator comprising an oil receptacle provided at its upper end with upstanding flanges to straddle a spring, a block insertable between said flanges to overlie the spring, inter-engaging means on said block and flanges for holding them against relative vertical movement, the lower side of said block being formed with a transverse groove and said flanges being provided with openings at the ends of said groove, a bolt passing through said openings and said groove, a plate underlying said block and having a rib received in said groove and contacting with the lower side of said bolt, spring means in said receptacle for forcing upwardly on the spring and downwardly on the receptacle, and capillary means for feeding oil from the receptacle to the spring.

3. A combined shock absorber and spring

lubricator comprising an oil receptacle provided at its upper end with upstanding flanges to straddle a spring, a bolt passing through said flanges to extend transversely over the spring, a plate underlying said bolt to lie upon the spring, the upper side of said plate having a groove receiving the lower side of said bolt, spring means in the receptacle to force upwardly on the spring and downwardly on the receptacle, and capillary means in said receptacle for feeding oil to the spring.

4. A combined shock absorber and spring lubricator comprising an oil receptacle having an open upper end, provided with a continuous laterally projecting flange at said upper end and provided also with two spaced vertical flanges rising from two opposite side portions of said lateral flange to straddle a spring, the portions of said lateral flange between said vertical flanges being formed with grooves, packings in said grooves to contact with the lower side of the spring, the inner sides of said vertical flanges being formed with shallow recesses T-shaped wicks having their head portions receive in said recesses and their shank portions disposed in said oil receptacle, means between the upper ends of the vertical flanges to lie upon the spring, and spring means in the receptacle to force downwardly on the latter and upwardly on the spring.

5. A device of the class described comprising a yoke structure embodying a member to abut a vehicle spring leaf, and side portions to straddle the spring, a fastener passing through said side portions, and a plate member between said side portions to abut the spring leaf opposite that above mentioned, said plate member having a groove receiving said fastener, one of said members being in the form of a spring to yieldably hold the leaves of the vehicle spring in contact with each other.

45 In testimony whereof I have hereunto affixed my signature.

WALKER H. SPAYD.
